OF WORCESTER, MASSACHUSETTS, A CORPORATION OF MASSACHUSETTS

FEEDING MECHANISM FOR GRINDING MACHINES

Application filed March 15, 1930. Serial No. 436,051.

This invention relates to a grinding machine and more particularly to a feeding mechanism for a grinding machine wheel slide for controlling the movement of the grinding wheel towards and from the work.

In grinding pins of crankshafts it is necessary to move the grinding wheel rearwardly through a considerable distance after one pin has been finished in order to bring the next pin into position for grinding. Heretofore, various mechanisms have been developed for rapidly moving a grinding wheel by power from this rearward position up to the work and then feeding it at a slow rate into the work until the desired size has been reached. It has been found in practice that the operators of these machines prefer, in many cases, to have the grinding operation under full control and carry it on at a rate and under such conditions as their own judgment and skill have determined to be the most satisfactory for the particular type of work being treated. Hence the power feed of the grinding wheel into the work has not, in every case, proven desirable. On the other hand, if it is necessary for the operator to manually move the grinding wheel slide from its rearward position up into a grinding position considerable time and effort would be wasted on his part and there would be danger of his carelessly feeding the wheel too far forward and accidentally running it into the work at a rapid rate and so injuring the wheel or the work. It is therefore desirable that the grinding wheel be moved by power through that portion of its travel in which it is out of contact with the work, but that the grinding operation itself be left wholly to the judgment and skill of the operator.

It is accordingly one object of this invention to provide a cross feed mechanism for a grinding machine in which the wheel may be rapidly moved forward towards the work by a power mechanism to a predetermined position adjacent to the work, whereupon the

power will be automatically disconnected and the wheel may then be fed manually until its further movement is brought to a stop by an adjustable mechanism.

A further object of the invention is to provide a construction in which the points at which the power mechanism is disengaged from the wheel slide, and at which the wheel slide is ultimately stopped, may be manually adjusted as desired.

A still further object of the invention is to provide a mechanism of this type which may be adjusted for a given work size, and then as the wheel wears away, the ultimate stopping position of the wheel and the position at which the power is disengaged may be simultaneously adjusted without changing their relationship to each other.

Other objects will be apparent from the following disclosure.

Referring to the drawings which illustrate one embodiment of this invention and in which like reference numerals indicate like parts:

Fig. 1 is a front elevation of the feed mechanism removed from the machine base;

Fig. 2 is a vertical transverse section, taken approximately on the line 2-2 of Fig. 1;

Fig. 3 is a top plan view showing the assembled mechanism; and

Fig. 4 is a fragmentary plan view of the mechanism, with a few parts removed to better show the construction.

In the embodiment of the invention illustrated in the drawings, a cylindrical grinding machine is provided in which the wheel slide may be rapidly moved in either direction by means of a power driven cross feed screw. The wheel slide is also movable by a finely adjustable, manually operable mechanism, and the ultimate stopping position of the wheel relative to the finished work size is determined by an adjustable stop which cooperates with the hand feed mechanism. In order that the wheel slide may be moved rapidly towards the work

from a rearward position, without material attention on the part of the operator, the power feed mechanism is arranged to be releasably connected to the cross feed screw, as by means of a clutch, and this clutch is actuated by a traveler mechanism which is movable in timed relation with the cross feed screw so that the clutch may be disengaged when the wheel has reached a predetermined position, preferably at a point just before it contacts with the work piece or immediately following an initial grinding cut. When the clutch has been disengaged the wheel may be fed forward by hand until the traveler mechanism has moved an arm or the like into the path of the adjustable stop of the cross feed mechanism, which serves to stop further forward movement of the wheel.

The invention further contemplates a hand lever which is so connected to the power mechanism that the operator may manually control the application of the power to the feeding mechanism in order to move the wheel in the desired direction toward or from the work piece to a predetermined extent before being automatically disengaged and the cycle of operations repeated. The hand lever mechanism also serves to automatically keep the hand feed wheel disengaged from the cross feed mechanism so that the operator cannot manually turn the feed screw while it is being rotated by the power mechanism.

Referring more particularly to the drawings which illustrate the invention as applied to a cylindrical grinding machine of standard construction, the machine comprises the usual work table (not shown) traversable on a V-way 12 constituting one of a pair of slide-ways which is formed on the base 14 of the machine. In accordance with standard grinding practice, it is understood that the work piece will be suitably mounted on centers carried by the work table and will be rotated by suitable mechanism during the grinding operation. As shown in Fig. 2, a rotatable grinding wheel 20 is arranged to be fed toward and from the work piece to grind it to a predetermined size. For this purpose, the wheel is suitably mounted on a slide 22 which in turn is mounted on a V-way 23 and a flat way (not shown) on a block 25 and is adapted to be moved by means of a half-nut 26 engaging a cross feed screw 27 arranged for movement by a feed mechanism of the type contemplated in the present invention.

The feed screw mechanism is so constructed and arranged that it may be operated either by hand or by power to accomplish a feeding movement of the grinding wheel. In the production grinding of crankshafts and the like, it is particularly advantageous to feed the grinding wheel rapidly toward the work and stop it at a position adjacent to the work surface whereupon it may be fed manually by the operator to precisely move

it to the proper grinding position relative to the crank shoulders. At the completion of the grinding operation, the wheel is quickly removed by power from an operative engagement with the work in order that the table may be traversed to bring the next crankpin into alignment with the grinding wheel. To control the rate of grinding feed during the grinding operation a hand wheel is provided by which the operator may manually feed the grinding wheel into the work at a proper rate to a position at which a stopping device becomes effective and prevents any further forward movement of the wheel but allows it to grind out to the desired size. In order that the feed mechanism may be operated by power to bring the wheel rapidly and quickly to a grinding position the feed screw 27 is provided with a gear 28 which meshes with a gear 29 fastened to one end of a rotatable shaft 30 which is mounted in suitable bearings on a frame 32 secured to the front of the machine base 14. A bevel gear 35 is mounted on the other end of the shaft 30 and meshes with a pair of bevel gears 36 and 37 each of which is mounted for rotation on a shaft 38 which is rotatably mounted in the frame 32 and arranged longitudinally of the base. The outer end of the shaft 38 is provided with a pulley 39 which is arranged to be driven from any suitable source of power. The gears 36 and 37 are preferably loosely mounted on the shaft 38 and are so arranged that either one may be connected to the power shaft 38 to transmit power to the gears 35, 29 and 28 to rotate the feed screw in the desired direction.

To positively connect the gears 36 and 37 to the power shaft 38 any one of the well known types of friction clutches may be utilized but for simplicity of illustration a double cone clutch member 40 is shown slidably keyed to the shaft 38 by a key 41 and having a pair of frusto-conically shaped surfaces 42 and 43 adapted to engage correspondingly shaped driving apertures 45 and 46 within the gears 36 and 37 respectively. It will be readily apparent from this construction that the operator may connect the clutch member 40 to either one of the gears 36 or 37 to rotate the feed screw 27 by power in the desired direction. This movable member 40 is provided with an annular groove 48 arranged for engagement by suitable actuating pins carried by a yoked member 50 so that by swinging the member 50 about a suitable pivot point, the clutch member 40 may be moved into engagement with either one of the driving apertures 45 or 46 to permit either one of the gears 36 or 37 to rotate the feed screw. A hand lever 51 is pivotally mounted on a stud 52 carried by a projection 53 extending from the frame 32 and it is provided with a pin 55 which is adapted to fit into an annular groove 56 formed in a spool-shaped member

57 secured to one end of a rod 58 which is slidably mounted in suitable bearing brackets 59 and 60 attached to the frame 32. The other end of the rod 58 likewise is provided with a second spool-shaped member 61 having an annular groove 62 which engages a pin 63 carried by a lever 64 which is fixedly mounted on a shaft 65 and keyed thereto by a key 66. The shaft 65 is suitably journaled in a boss 67 on the front of the frame 32 and it is arranged to project within the interior of the base. The yoked member 50 is mounted on this inner projecting portion of the shaft 65 and is suitably keyed thereto.

15 It will be readily apparent from this construction that any movement of the lever 51 toward the left by the operator to a position 51a, as viewed in Fig. 1, will impart corresponding movements to the rod 58, the lever 64 and the yoked member 50 to slidably engage the clutch member 40 with the bevel gear 36 whereby it may positively rotate the feed screw to produce a forward movement of the nut 26 attached to the slide 22 and thereby move the grinding wheel toward the work piece. Likewise, if the lever 51 is moved toward the right to take the position 51b, as viewed in Fig. 1, it will impart corresponding movements to the rod 58, the lever 64, the yoked member 50 and the clutch member 40 in that direction to connect the gear 37 to the shaft 38 and thereby rotate the feed screw to rearwardly move the grinding wheel away from the work piece.

35 In order that the clutch member 40 may be normally held in a neutral position and also that it may be returned to this position when the hand lever 51 is released by the operator, a mechanism is provided which comprises a pair of opposed springs so mounted that their respective spring pressures counteract each other to automatically return the clutch member to a neutral position. To this end a spring 70 is loosely positioned on the rod 58 and interposed between the flange 71 of the rod 58 and the face 72 on the bearing member 59. In a like manner, a second spring 75 is also loosely positioned on the rod 58 and interposed between the flange 71 and the face 76 on the bearing 60. It will thus be seen from this construction that any movement of the hand lever 51 in either one of these directions will compress one of the springs 70 or 75 respectively and consequently it will be necessary for the operator to hold the lever 51 in its respective position to permit the power feed to move the grinding wheel through the desired distance toward or from the work. If at any time during this travel the operator releases his grasp on the lever 51 the resilient energy of the spring 70 or 75 respectively, resulting from the releasing of the compressive force of that particular spring, will move the rod 58 sufficiently to slide the clutch member 40 into a neutral position. It

can be seen that it will not be necessary for the operator to manually move the lever 51 to this neutral position to stop the feeding movement; he need only to release his grip on the lever so that it may spring back of itself. 70

In order that the power mechanism may properly disengage the clutch at a predetermined point of the wheel travel, a traveler member is provided which is arranged to be driven in timed relation with the power shaft. 75

To accomplish this purpose, a shaft 78 is mounted for rotation in suitable bearings in the frame 32 and carries a gear 80 keyed to one end thereof which meshes with the gear 28 so that it may rotate when the feed screw 80

is operated by power. The other end of the shaft 78 is suitably provided with an enlarged hub or body portion 79 which is mounted for rotation in a front apron plate 81 integral with the frame 32 and carries a 85

spiral pinion 83 loosely mounted for rotation thereon which meshes with another spiral gear 84 fixedly mounted on a flanged sleeve 85 by means of a key 86. This sleeve 85 is mounted for rotation about a rotatable screw

shaft 88 and supported for rotation within a bearing bracket 89. The shaft 88 extends through the bearing bracket 89 and carries a releasable coupling attached thereto which is connectable with the gear 84. The other 95

end of the shaft 88 is supported in a bearing bracket 90 which is secured by suitable screws to the apron plate 81. The gear 83 may be adjustably positioned with respect to the shaft 78 by means of a micrometer ad-

justing device 91 which comprises a worm 92 rotatably supported in a housing 93 integral with the gear 83 and mounted for rotation about a sleeve 94 so that it may be revolved thereabout and locked in adjusted positions on a worm wheel 95 which is keyed to the sleeve 94 by a key 96. Adjoining the hub 79 and integral therewith and the shaft 78 is a smaller hub member 77 on which the sleeve 94 is loosely mounted for rotation thereon. 100

In order that the cross feed screw may be rotated manually when the power is disengaged a handwheel 97 is provided which carries a hub 98 loosely mounted on the sleeve 94 and slidably therealong but in driving re-

lationship therewith, such as by means of a key and keyway suitably located in the parts. The hub 98 is provided with clutch teeth 99 which are suitably formed thereon for engagement with a set of similar teeth 100 on 105

the worm wheel 95. In order that the driving connection between gear 83 and the shaft 78 positively operative by power, a suitable clutch mechanism of the spring pressed plunger type may be utilized 110

but in the preferred construction it may comprise a sleeve member 101 which is rigidly fastened on a reduced extension 102 of the shaft 78 by a key 103 and is arranged for sliding movement therealong. The sleeve 101 115

120

125

130

is provided with a reduced end portion 104 which is adapted to fit within the sleeve 94 and its body portion is suitably shaped to provide a hub 105 to support the hand wheel 97 and which may rotate with the hub 98. The inner face of the hub 105 is provided with teeth 106 which suitably engage other teeth 107 extending from the front end of the sleeve 94. To hold the teeth 106 and 107 in proper driving engagement a spring 109 is loosely fitted into a cylindrical cavity 110 within the sleeve 101 and positioned on the extension 102 so as to be interposed between the flange 112 on the extension 102 and the inside face 113 of the cavity 110. The hub 105 extends outwardly from the hand wheel hub 98 and is shaped to form a stepped collar which serves to hold the hand wheel 97 in place on the sleeve 94 and also provide a means for disengaging the teeth 106 and 107.

In order to properly connect the shaft 88 to the power feed, a suitable spring pressed coupling mechanism is utilized and as illustrated it comprises a flanged sleeve 115 which is slidably keyed by means of a key 116 to the extension of the shaft 88 which overhangs the bearing bracket 89 and it is provided at one end with a large flange 118 which is arranged to be held against the corresponding-shaped flange 119 formed on the sleeve 85 and connected in driving relation therewith by means of a pin 120. A spring 121 arranged within a recess 122 of the sleeve 115 and interposed between the bottom face 123 of the recess and the retaining nuts 125 serves to hold the flanges 118 and 119 in the proper driving engagement. A flange 126 is provided on the open end of the sleeve 115 for the purpose of manual adjustment.

To positively disconnect the power feed mechanism, means are provided which automatically become effective when the wheel slide reaches a predetermined point. Further movement of the slide will throw a stop into the path of a movable abutment connected to the cross feed mechanism so as to prevent further forward feeding of the grinding wheel by hand. To accomplish this, a non-rotatable nut is longitudinally moved by a screw geared to the cross feed screw and adapted to engage a finger which is arranged to be moved into and out of its path of movement to disconnect the power clutch and then after a predetermined number of revolutions of the screw by hand to engage a stop lever and move it into the path of an abutment associated with the hand wheel which is employed to rotate the screw. As shown in the present embodiment of the invention, a non-rotatable nut 127 is arranged for travel longitudinally along the screw 88 and it is held against rotation against a flat guideway 128 by means of a suitable flat portion 129 provided on the side portion of the nut 127.

In order that the clutch 40 may be thrown automatically a lever 130 having a hub portion 131 is pivotally mounted on a stud 132 attached to the front plate 81. A pair of spaced fingers 133 and 134 are mounted in a staggered relationship on the outer surface of the hub 131 and are arranged for movement into and out of the path of travel of the nut 127 by means of a link member 135 pivotally connecting the lever 130 with the lever 64. In order that this connection may be adjusted so that the nut 127 will strike the fingers 133 and 134 respectively at the proper position, adjustable contact members 137 and 138 are provided which are mounted on the depending lugs 139 and 140 respectively, formed on the nut 127. From this construction it will be readily apparent that when the nut 127 is moved in a forward direction the member 138 will contact with the finger 133 to swing the levers 130, 64 and 51 to a neutral position, as shown in Fig. 1, thus disconnecting the power feed.

To positively stop the cross feed mechanism at a predetermined point after a predetermined number of revolutions of the screw by the hand wheel, a stop lever 141 is provided having a relatively long arm 142 and a short arm 143 which is forked to straddle the screw 88, the lever being pivoted on a stud 144 on the front plate 81. The lever 141 is preferably held in an inoperative position, as shown in Fig. 1, by means of a spring 145 which is positioned loosely on the screw 88 and interposed between the cheek 146 of the bearing bracket 90 and the side face 147 of the arm 143 so as to move the lever arm 142 to an inoperative position as shown in dotted lines in Fig. 1 and out of the path of a movable abutment 148 carried by the arm 149 attached to the housing 93.

In order that the manual feed mechanism may be automatically connected when the power is disengaged a lever 150, fixed on a shaft 152 by a key 153, carries a T-shaped member 154 having a pair of flat portions 155 and 156 which are arranged on each side of the "T" respectively and separated by a V-shaped groove 158 for the reception of a pin 159 projecting from the hand lever 51. The contact member 154 and the pin 159 are held in engagement at all times by a spring 160 which is suitably fastened to the bracket 60 and an arm 161 fixed on the shaft 152. The shaft 152 is rotatably mounted in suitable bearing members 163 and 164 carried by the brackets 59 and 60 respectively, and it has a yoked member 165 which is securely fastened to the other end thereof by means of a suitable key or the like. In order that the yoked member 165 may move the hand wheel 97 into and out of engagement with the feed screw mechanism when the hand lever 51 is in a neutral position, it is provided with suitable pins 167 and 168 which fit into an

annular groove 169 formed in the hub 98 of the hand wheel 97. It can be seen that by swinging the yoked member 165 about its pivot the hand wheel 97 will slide longitudinally along the sleeve 94 to engage the clutch teeth 99 and 100 and operatively connect it with the housing 93.

In setting up the machine for a given piece of work, the operator must make certain adjustments of the parts. To do this the work is first ground to the required size by manually feeding the wheel into the work piece and noting the size readings as indicated by a dial gauge. When the work has reached the correct size, the machine is stopped and with the grinding wheel still in contact with the finished work piece the stop 142 is moved, by the operator, downwardly into the path of travel of the abutment 148 and against the pressure of the spring 145. The sleeve 101 is disengaged from the sleeve 194 thereby leaving the housing 93 and the spiral gear 83 free to be turned about the shaft 78 by the hand wheel 97 so that the abutment 148 may be moved into engagement with the end of the stop 142, after which the sleeves 94 and 101 are reengaged. When the above adjustments have been made and with the stop 142 held in this position against the abutment 148 by the operator, the flanges 118 and 119 are disengaged and the pin 120 removed from driving relation therewith, so that the screw 88 may be freely rotated manually by the flange 126 to move the traveler 127 longitudinally therealong until it contacts with the arm 143 forming a part of the stop 142, whereupon the flanges 118 and 119 and the pin 120 are reengaged.

Following this, the next adjustment to be applied is to the power disengaging stops for the forward and rearward movement of the grinding wheel. To accomplish this, the hand lever 51 is moved by the operator to a position 51a, as shown in dotted outline in Fig. 1, thereby applying power to feed the grinding wheel in a forward direction towards the work until it nearly contacts with the work piece. At this point the operator releases his grasp on the hand lever 51 and it immediately springs back to a neutral position as shown in full lines in Fig. 1 thereby disconnecting the power from the feed screw and stopping the wheel. The power is turned off and the lever 51 again moved to take the former position 51a thereby moving the finger 133 to a vertical position by means of the link members 130, 135 and 64, and while in this position, the dog 138 is moved into contact with it. The lever 51 is allowed to spring back to its neutral position thereby moving the finger 133 from its vertical position and the parts take the positions as shown in Fig. 1, after which the dog 138 is advanced a few additional turns 65 in order that it will contact with the finger

133 and start it moving slightly in advance of the stopping position of the wheel. Next, the wheel is moved to its maximum rearward position and a similar adjustment is made to the dog 137 and the finger 134 with the lever 51 occupying a corresponding position 51b instead.

In order to compensate for wheel wear, an adjustment is made to the finished size stop, and this is accomplished by means of the micrometer mechanism 91 by which the abutment 148 may be repositioned relative to the worm wheel 95. This repositioning operation accomplishes two things; namely, to move the abutment face 148 by small increments away from the stop 142 in order that the abutment may move a short distance to compensate for the wheel wear in the finished work size, and also to automatically relocate the traveler with respect to the wheel slide to provide a correction for wheel wear in the stopping mechanism due to the fact that the micrometer mechanism serves as the driving medium. These dog and stop adjustments, when once made, are kept fixed with the exception of the small increment adjustments to compensate for wheel wear.

When a new wheel is installed it will be necessary for all the adjustments to be changed and the same adjusting processes gone through again with the exception of the adjustment of the stops 137 and 138. The positions of these stops on the traveler 127 is dependent upon the work diameter and independent of the wheel diameter so that when once adjusted their relationship will be fixed with respect to the traveler and need not be changed except when the work diameter is changed. With this device, the one adjustment for wheel wear in the finished size stop automatically compensates for wheel wear for the traveler.

As heretofore stated, this mechanism is primarily designed to be used in a machine for the grinding of crankshafts or for doing special types of work in which the mechanism is set up for one particular size of work piece and the adjustments are kept fixed for that particular type of work, being changed only when the machine or apparatus is changed for another character of work. Hence, for work of this sort the only adjustments which are necessary are those which must be made at the time of wheel replacements, namely the setting of the finished size stop and the traveler stop relative to the feed screw.

The operation of the mechanism is readily apparent from the foregoing disclosure. When the operator moves the hand lever 51 towards the left, as viewed in Fig. 1, to hold it in a position 51a against the pressure of the spring 75, this movement serves to engage the clutch member 40 to cause an inward feeding movement of the grinding wheel by power

toward the work and to simultaneously cause the traveler nut 127 to move longitudinally along the screw shaft 88 until the contact member 138 thereon strikes the finger 133, which has been thrown into its path by the movement of the lever 51. The forward feeding movement of the grinding wheel by power continues while the nut 127 moves further along the screw 88, towards the left, during which movement the contact member 138, through the finger 133, lever 130, link 135, lever 64 and rod 58, applies pressure to overcome the holding pressure maintained by the operator on the lever 51 until it swings the lever 130 and mechanism connected therewith far enough to disconnect the clutch 40 and thereby stop the power infeed at the desired point. Simultaneously with the swinging of the lever 130 to disengage the clutch 40, the rod 58 which is connected with the lever 51, moves the lever 51 from the dotted position 51a, as shown in Fig. 1, to its neutral position, as indicated in full lines in Fig. 1. This latter movement of the lever 51 serves to move the pin 159 along the flat way 155 until it drops into the V-groove 158 in the member 154, thereby sliding the hand wheel 97 into operative engagement with the wheel feeding mechanism to permit the operator to feed the wheel manually during the grinding operation.

After the work piece has been ground to the desired size, the hand lever 51 may be moved by the operator towards the right, as viewed in Fig. 1, and there held by him in a position 51b against the pressure of the spring 70, this movement serving to engage the clutch member 40 to thereby remove the grinding wheel by power rapidly from the work and to a rearward position. The rearward movement of the grinding wheel continues until the contact member 137 strikes the finger 134, which projects in its path, and swings the lever 130 and its connected mechanism towards the left to overcome the holding pressure applied to the lever 51 by the operator and to disengage the power clutch. It will be apparent that during the power operation of the feed screw, any movement of the hand lever 51 to either one of the positions 51a or 51b will slide the pin 159 along the flat ways 155, or 156 respectively and thereby rock the member 154 away from the plate 81 with the flat faces 155 or 156 being held into contact with the pin 159 by the spring 160. This movement is communicated to the yoked member 165 to move it a corresponding amount in order to prevent the hand wheel 97 from being thrown into engagement with the worm wheel 95 during the power infeed. The contact member 138 is adjustable so that the power feed may be varied so that it may be thrown out at any desired point during the wheel travel. While the wheel is being fed manually by the operator the traveler 127 is further moved along the

screw 88 until it contacts with the arm 143. The contact member 138 is interposed by this movement into the path of the finger 133 and thereafter prevents the clutch 40 from being engaged to cause the wheel slide to be moved further by power in the same direction while it is being moved manually. 70

The operation of the device will be apparent in view of the above explanation, and it will be obvious that various modifications 75 may be made therein within the scope of the claims appended hereto.

Having thus described the invention, what is claimed as new and desired to secure by Letters Patent is:

1. A cross feed mechanism for a grinding machine slide comprising a manually operable feed screw connected to the slide, a power mechanism connectible to rotate the feed screw, means including a contact member to disconnect said power mechanism from the screw, a stop mechanism to stop the slide at a predetermined position, and a traveler movable in timed relation with the feed screw to actuate successively said contact member and 90 said stop mechanism.

2. A cross feed mechanism for a grinding machine slide comprising a manually operable feed screw connected to the slide, a power mechanism, a clutch mechanism including a contact member for connecting the power mechanism to the screw, mechanism including an adjustable stop to stop the slide at a predetermined point, a traveler movable in timed relation with the feed screw to actuate said contact member and said stop mechanism successively to throw the clutch and thereafter to stop the wheel slide, and means for adjusting the position of the traveler relative to said stop mechanism. 100 105

3. A cross feed mechanism for a grinding machine slide comprising a manually operable cross feed screw connected to move the slide, a power mechanism to rotate the feed screw, means including a contact member for disconnecting said mechanism from the feed screw when the slide has reached a predetermined point, adjustable mechanism including a positive stop to limit the subsequent manual movement of the slide, a traveler movable in timed relation with the feed screw to actuate successively said contact member and said stop mechanism, and means for simultaneously adjusting the positions of said stop and said traveler with respect to the feed screw to compensate for wheel wear. 110 115 120

4. A cross feed mechanism for a grinding wheel slide comprising a manually operable feed screw connected to the slide, a power mechanism, a clutch to connect the power mechanism to rotate the feed screw in either direction, means including a contact member to operate the clutch and disconnect said power mechanism from the screw when the slide has reached any predetermined position, 130

and a traveler movable in timed relation with the feed screw to actuate said contact member and disengage the clutch, and thereafter prevent the power mechanism from being connected to move the wheel slide further in the same direction while the slide is being moved manually.

Signed at Worcester, Mass., this 13th day of March, 1930.

GEORGE H. SMITH.
